CLAIM

The ornamental design for a pendant or charm, as shown and described.

DESCRIPTION

FIG. 1 is a right front perspective view of a pendant or charm; FIG. 2 is a left rear perspective view of the pendant or charm of FIG. 1;

FIG. 3 is a front elevational view of the pendant or charm of FIG. 1;

FIG. 4 is a rear elevational view of the pendant or charm of FIG. 1;

FIG. 5 is a left side elevational view of the pendant or charm of FIG. 1;

FIG. 6 is a right side elevational view of the pendant or charm of FIG. 1;

FIG. 7 is a top plan view of the pendant or charm of FIG. 1; and,

FIG. 8 is a bottom plan view of the pendant or charm of FIG. 1.

The broken lines shown in the drawings represent portions of the pendant or charm which form no part of the claimed design.
